US0D1072051S

(12) **United States Design Patent** (10) **Patent No.:** **US D1,072,051 S**
(45) **Date of Patent:** **** Apr. 22, 2025**

(54) **DIGITAL SIGNAGE**

(71) Applicant: **LG ELECTRONICS INC.**, Seoul
(KR)

(72) Inventors: **Jaewon Lim**, Seoul (KR); **Seungdon Lee**, Seoul (KR)

(73) Assignee: **LG ELECTRONICS INC.**, Seoul
(KR)

(**) Term: **15 Years**

(21) Appl. No.: **35/519,976**

(22) Filed: **Aug. 9, 2023**

(80) **Hague Agreement Data**

Int. Filing Date: **Aug. 9, 2023**

Int. Reg. No.: **DM/231077**

Int. Reg. Date: **Aug. 9, 2023**

Int. Reg. Pub. Date: **Feb. 9, 2024**

(30) **Foreign Application Priority Data**

Mar. 23, 2023 (KR) 30-2023-0010870

(51) **LOC (15) Cl.** **20-03**

(52) **U.S. Cl.**

USPC **D20/42**; D20/10; D14/126
